(57) **CLAIM**

The ornamental design for an electronic cigarette, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first embodiment of an electronic cigarette in accordance with our new design;

FIG. 2 is a right side view thereof;

FIG. 3 is a left side view thereof;

FIG. 4 is a rear view thereof;

FIG. 5 is a top plan view thereof;

FIG. 6 is a bottom plan view thereof;

FIG. 7 is a front view of a second embodiment of an electronic cigarette in accordance with our new design;

FIG. 8 is a right side view thereof;

FIG. 9 is a left side view thereof;

FIG. 10 is a rear view thereof;

FIG. 11 is a top plan view thereof;

FIG. 12 is a bottom plan view thereof;

FIG. 13 is a front view of a third embodiment of an electronic cigarette in accordance with our new design;

FIG. 14 is a right side view thereof;

FIG. 15 is a left side view thereof;

FIG. 16 is a rear view thereof;

FIG. 17 is a top plan view thereof;

FIG. 18 is a bottom plan view thereof;

FIG. 19 is a front view of a fourth embodiment of an electronic cigarette in accordance with our new design;

FIG. 20 is a right side view thereof;

FIG. 21 is a left side view thereof;

FIG. 22 is a rear view thereof;

FIG. 23 is a top plan view thereof;

FIG. 24 is a bottom plan view thereof;

FIG. 25 is a front view of a fifth embodiment of an electronic cigarette in accordance with our new design;

(Continued)

FIG. 26 is a right side view thereof;
 FIG. 27 is a left side view thereof;
 FIG. 28 is a rear view thereof;
 FIG. 29 is a top plan view thereof;
 FIG. 30 is a bottom plan view thereof;
 FIG. 31 is a front view of a sixth embodiment of an electronic cigarette in accordance with our new design;
 FIG. 32 is a right side view thereof;
 FIG. 33 is a left side view thereof;
 FIG. 34 is a rear view thereof;
 FIG. 35 is a top plan view thereof; and,
 FIG. 36 is a bottom plan view thereof.
